TRIMMER MECHANISM

Application filed September 9, 1927. Serial No. 218,390.

The invention relates generally to wheel trimming devices and more particularly to trimming devices for abrasive wheels of a type suitable for grinding purposes.

5 An object of our invention is to provide a device for trimming the working surfaces of abrasive wheels to a contour suitable for grinding gear teeth and which may be utilized to trim abrasive wheels for grinding 10 gear wheels of any desired involute tooth form, pitch or diameter.

Heretofore trimmer mechanisms utilized for trimming the working faces of abrasive wheels to form contours suitable for grinding 15 gear teeth have been provided with a cam or template to guide the trimming member. The working surface of the cam was made either similar to or identical in shape with the tooth contour it was desired to provide, or the cam was made of an entirely dissimilar shape in order to impart the proper motion to the trimming member through the medium of a compound linked mechanism. However, these machines had the inherent 20 disadvantage of indirect operation and the resulting inaccuracies introduced by looseness or deflections in the connecting link mechanism. Further, very careful workmanship was required in the construction and 25 operation of such machines to produce accurately trimmed abrasive wheels.

The present invention relates to a trimming device for abrasive wheels that may be utilized in grinding gear teeth, and 25 that operates upon the principle of direct generation of the desired tooth contour including the involute or working portion, the flank and the root fillet of the tooth upon the working faces of the abrasive wheel.

40 The device comprises in general a supporting base, a frame member pivotally mounted on the supporting base and a pair of spaced cylindrical segments, of diameter 45 equal to that of the base circle of the gear wheel to be ground, pivoted to the frame member. Connected tangent bars are mounted on the peripheries of the cylindrical segments in such a manner that they are free to 50 roll as a unit thereon but are restrained

from tangential or radial displacement with respect thereto.

An arcuate trimmer arm is pivotally mounted on the tangent bars and latched to the connecting member between the bars. A 55 trimming member such as a cutting diamond is adjustably mounted on the trimmer arm in such manner that it lies in the plane described by the bearing faces of the tangent bars. Adjusting means are provided to regulate the 60 angular position of the cylindrical segments with respect to the frame member in order to provide working faces of the proper width on the abrasive wheel to correspond with the desired tooth space of the gear wheel to be 65 ground.

In operation, the abrasive wheel to be 70 trimmed is rotated at a moderate speed and slowly fed into engagement with the trimming member. The tangent bars are rolled on the cylindrical segments to cause the 75 trimmer member to describe an involute curve from the base circle outward to trim the abrasive wheel to the shape of the working portion of a gear tooth. The tangent bars 80 may then be held stationary in a predetermined limited position and the trimmer arm unlatched from them and oscillated about its 85 pivotal axis to cause the trimming member to describe an arc from the base circle inward to trim the abrasive wheel to a contour suitable for grinding the flank and root fillet of a gear tooth. After the trimming operation has been completed on one side of the 90 abrasive wheel the frame may be turned 180° upon the pivotal supporting base and accurately set in the proper position to trim the other side of the wheel to an identical contour.

In the accompanying drawing, 90 Figure 1 is a plan view partially in cross-section of a wheel trimming device embodying the principles of our invention;

Fig. 2 is a view in end elevation of the 95 trimming device of Fig. 1;

Fig. 3 is a view in side elevation thereof.

Fig. 4 is a view in section of a portion of the trimming device taken along the line IV—IV of Fig. 1; and

Fig. 5 is a view in section of the trimmer 95

arm pivot mechanism taken along the line V—V of Fig. 4.

Referring to the drawing, the illustrated embodiment of the invention comprises a supporting base or center plate 1 that is adapted to be secured to a machine frame 2 by means of bolts 3. A center pin 4 is pressed into the base 1 and a frame or trunnion supporting member 5 is disposed on the pin in such manner as to permit it to be set in different positions to meet operating conditions.

Locking screws 6 are provided for clamping the frame 5 securely to the center pin 4 after the proper adjustment has been made.

Threaded gauge pins 7 and 8 are disposed in the frame 5 and lock nuts 9 are provided for retaining the gauge pins in the positions to which they may be adjusted. It will be noted that the pins 7 and 8 are disposed to engage opposite sides of a stop pin 11 that is threaded into the base 1 when the frame 5 is oscillated on the pin 4. Accordingly the frame 5 may be given an angular movement of substantially 180°.

T slots 13 are provided in the end portions of the frame 5 and extend parallel to each other and parallel to the center pin 4. In order to mount a base circle adjusting arm 17, square headed bolts 14 provided with nuts 15 are mounted in the T-slots 13 to serve as trunnions to receive sleeve bearings 16 formed integral with the adjusting arm 17.

Two cylindrical segments 18 having clamping hubs 19 and clamping bolts 21 are mounted upon the bearing sleeves 16 and clamped thereto. The cylindrical segments 18 have radii equal to the radius of the base circle of the gear wheel for which an abrasive wheel 40 is to be trimmed. The adjusting arm 17 is provided with an opening 22 in its mid portion for receiving a stop pin 23. As shown in Fig. 1, the stop pin 23 is provided with a square head 24 and is mounted in a T-slot 25 in the frame 5 in such manner that it may be adjusted parallel to the center pin 4 and locked in any predetermined position by a nut 26.

Adjusting screws 27 and 28 are provided in the adjusting arm 17 for engaging the stop pin 23 to turn the adjusting arm 17 and the attached segments 18 about the trunnion bolts 14 for a purpose to be hereinafter described.

Tangent bars 31 and 32 having an integral connecting bar 33 are mounted upon the peripheries of the segments 18 in such manner that they are free to roll thereon and are restrained from axial displacement with respect thereto by the engagement of segment flanges 36 in grooves 34 and 35 in the tangent bars 31 and 32, respectively. The tangent bars 31 and 32 and the segments 18 are provided with aligned grooves 37 and 38 respectively in their engaging faces for re-

ceiving wires 44 and 45 disposed to prevent tangential displacement of the tangent bars with respect to the segments 18.

Lugs 40 and 41 are provided upon the connecting bar 33 for receiving adjusting screws 70 42 and 43.

One end of each of the wires 44 and 45 is attached to the adjusting screws 42 and 43, respectively. The wires 44 and 45 pass around knobs 46 and 47 respectively on the connecting bar 33, through the grooves 38 and 37 in the tangent bars and segments and are secured at their other ends to screws 48 in the segments 18.

Other wires 51 and 52 have both their ends secured to screws 53 mounted in the segments 18 at the ends opposite to those occupied by the screws 48. The wires 51 and 52 are doubled and pass through the slots 37 and 38 in the segments and tangent bars respectively in such manner that the two portions of them occupy positions at either side of the wires 44 and 45. The looped portions of the wires 51 and 52 are guided by suitable knobs and are passed around small pulleys 54 and 55 that are pivoted on adjusting screws 56 and 57.

Independent mechanical means are provided in the form of wheeled carriages 61 and 62 that are mounted upon the tangent bars and supported radially from the trunnion sleeves 16 to keep the tangent bars in contact with the segments 18. The faces of the tangent bars 31 and 32 opposite to the faces that are in engagement with the segments 18 are provided with central grooves 63 that are adapted to engage flanged wheels 64 of the carriages 61 and 62.

The carriages 61 and 62 comprise frames 65 that are substantially rectangular metal blocks provided with slots at either end in which the flanged wheels 64 are pivoted upon axles 66. A plate 67 is provided upon each carriage to serve as an anchor for the ends of wires 68 that extend from the carriage around small grooved pulleys 69 which are journaled upon the bearing sleeves 16 at either side of the segment clamps 19. This arrangement provides a doubled wire extending from the carriage to the trunnion assembly on each side of the segments 18.

An adjusting screw 71 having a locking nut 72 is threaded in the plate 67 and bears upon the carriage frame 65. The purpose of this adjusting screw is to lift the plate 67 from the carriage frame 65 thereby applying tension to the wires 68 and forcing the carriage into engagement with the tangent bar to prevent radial displacement of the bar with respect to the segments 18.

Stop discs 81 are mounted upon arms 82 that are extensions of the frame 5. The discs are mounted in the same plane with the segments 18 and serve as stops for the tangent 130

arms 31 and 32 at a position which is determined by the diameter of the stop disc.

In order to provide means for pivotally attaching a trimmer arm to the tangent bars 31 and 32, they are each provided at their ends with bracket members or eccentric arms 86 and 87, respectively, that extend backwardly parallel to the bars and within the frame 5. The eccentric arms 86 and 87 are each provided with circular openings 88 that are disposed adjacent similar circular openings 94 in the ends of an arc shaped trimmer arm 95. For the purpose of pivoting the trimmer arm 95 on the eccentric arms 86 and 87, the openings 88 and 94 are provided with eccentric discs 91 and 93, respectively.

As shown in Figs. 4 and 5, each of the discs 91 is provided with two tapped holes 90 disposed at different distances from the center 20 for receiving a pivot pin 92. Also, each of the discs 93 is provided with two cone bearing surfaces 100 for receiving the end of the pivot pin 92, in such manner that the trimmer arm 95, when mounted, is free to be turned relative to the tangent bars 31 and 32 about an axis through the centers of the pivot pins 92.

The purpose of mounting the pivot pins 92 in eccentric discs is to provide means for changing the position of the pivot axis of the 30 trimming arm 95 with respect to the tangent bars 31 and 32. In operation, the pivot pin 92 is inserted in either of the holes 90, and the discs 91 and 93 are turned within the openings 88 and 94 until the desired setting 35 of the pivot centers is obtained. The discs 91 and 93 may then be clamped in position by means of clamping screws 89. The position of the pivot pin 92 with respect to the trimming arm 95 may be ascertained by means of graduations 96 that are provided on the peripheries of the eccentric discs 93. The trimmer arm 95 is provided at its center with a cylindrical handle portion 97 which may be latched to the connecting bar 33 by means of the latch 45 98. A trimming member 101 such as a cutting diamond is mounted within the cylindrical portion 97 of the trimmer arm 95 by means of a threaded diamond holder 102.

The diamond holder 102 may be adjusted 50 longitudinally of the cylindrical handle 97 by means of its threaded engagement therewith and may be locked in any desired position by means of lock nuts 103.

An abrasive wheel 105 to be trimmed may 55 be rotatably mounted upon a suitable arbor 106 in such position that its axis is at right-angles to the axis of the center pin 4 and also perpendicular to the plane passing through the axis of the pivot pin 4 and the axis of the 60 trunnion bolts 14. Suitable means are provided for feeding the wheel 105 towards the trimming mechanism along the line of the axis of the pivot pin 4.

In operation, the trimming mechanism is 65 adjusted by turning the segments 18 upon

their axes and changing the position of the trimmer pin 101 as hereinbefore described, so that the point of engagement of the trimmer member and the blank to be worked on intersects the surface of a cylinder described by the segments 18 at a distance equal to $\frac{1}{2}$ of the tooth space, as measured on the base circle of the gear wheel to be ground, from the center line of axis of the pivot pin 4 when the tangent bars 31 and 32 are in engagement 70 with the stop discs 81.

The wheel 105 to be trimmed may then be rotated at a moderate speed and fed into light engagement with the trimmer member 101. The tangent bars 31 and 32 together with the trimmer arm 95 and trimmer holder 102 may then be rolled upon the peripheries of the segments 18 to cause the trimming point 101 to describe an involute curve which corresponds to the contour of a gear tooth from the base 85 circle to the tooth tip. Successive cuts are taken from the abrasive wheel 105 in this manner until the desired contour is obtained.

The trimmer arm 95 may then be unlatched from the connecting bar 33 by releasing the latch 98 and pivoted about the pivot pin 92 to cause the trimmer member 101 to trim the periphery of the abrasive wheel to an arcuate contour that is adapted for grinding the portion of a gear tooth from the base circle 95 to the root of the tooth, which is also known as the flank and root fillet of the gear tooth.

When one face of the abrasive wheel 105 has been trimmed to provide the proper contour, the clamping bolts 6 in the frame 5 may 100 be released and the entire frame and attached mechanism may be rotated about the center pin 4 through an angle of 180° , as determined by the stop pin 11, to the proper position for trimming the other face of the abrasive wheel 105.

As viewed in Fig. 1, the trimmer mechanism may be rotated clockwise about the center pin 4 until the gauge pin 8 comes into engagement with the stop pin 11. The trimming operation may be repeated on the second 110 face of the abrasive wheel, thereby providing two working faces adapting it to grind the adjacent faces of two gear teeth.

It is evident from the foregoing description 115 of the invention that a trimmer mechanism made in accordance therewith is adapted to accurately trim the working surfaces of an abrasive wheel for grinding gear teeth to the proper contours for the involute working portion, the flank portion and the root fillet.

It is further obvious that because of the 120 adjustments provided in our device, any desired combination of involute and arcuate contours may be secured for trimming abrasive wheels to grind gear wheels of any pitch, involute tooth form or diameter. A further advantage is obtained by constructing our trimmer mechanism in such manner that the same trimming member and guiding mecha- 125

nism may be used to trim each side of the abrasive wheel thereby ensuring exactly the same contour on each side thereof.

Although we have described a specific embodiment of our invention, it will be obvious to those skilled in the art that various modifications may be made in the details of construction and the design and proportions of the several cooperating parts of our trimmer mechanism without departing from the spirit and scope of the invention as set forth in the appended claims.

We claim as our invention:

1. A trimmer mechanism for abrasive wheels comprising a base member, a frame pivoted on the base member, cylindrical segments pivoted on said frame about their aligned geometrical axes, said segments having their axes disposed at right angles to the pivotal axis of the frame on the base member, tangent bars mounted to roll upon said segments and a trimmer secured to said tangent bars.

2. A trimmer mechanism for abrasive wheels comprising a base member, a frame supported on said base member, a plurality of cylindrical segments pivoted on the frame, tangent bars mounted on the segments and adapted to roll thereon, and a trimmer member pivoted to the tangent bars and adapted to roll with them or to pivot independently of them to trim the abrasive wheel.

3. A trimmer mechanism for abrasive wheels comprising a base member, a frame carried by the base member, a plurality of cylindrical segments mounted on the frame, tangent bars adapted to roll on the peripheries of the segments, a trimmer carried by the tangent bars, means for preventing the tangential displacement of the tangent bars and means comprising wheeled carriages mounted on the tangent bars and radially supported from the centers of the segments for maintaining the tangent bars in contact with the segments.

4. A trimmer mechanism for abrasive wheels comprising a base member, a frame member pivoted on the base member, cylindrical segments having their geometrical axes pivoted upon the frame member at right angles to the pivotal axis of said frame member, tangent bars mounted upon the peripheries of the cylindrical segments, said bars being free to roll thereon and restrained from tangential displacement with respect thereto, a trimmer member pivoted to the tangent bars, means for latching the trimmer member to the tangent bars and means for adjusting the pivotal center of the trimmer member with respect to the tangent bars.

5. In a mechanism for trimming abrasive wheels for grinding gear teeth, a cylindrical segment of radius equal to the base circle radius of the gear-wheel to be ground, a tangent bar adapted to roll upon the periphery

of the segment, a trimmer arm pivoted and latched to said tangent bar, a trimmer point carried by the trimmer arm, a stop member for engaging the tangent bar when the trimmer point is on the periphery of the base circle, said trimmer arm being adapted to pivot to trim the wheel to an arcuate contour within the base circle.

6. A trimmer mechanism for abrasive wheels comprising a base member, a frame member, cylindrical segments pivoted on the frame member, means for adjusting the angular position of the frame member with respect to the base member, means for adjusting the angular position of the segments with respect to the frame member, tangent bars disposed to roll on the segments, a trimmer arm carried by the tangent bars, and a trimmer mounted on the trimmer arm.

7. A trimmer mechanism for abrasive wheels comprising a cylindrical segment, a tangent bar mounted to roll upon the periphery of said segment, a trimmer arm pivoted to said tangent bar, a trimmer carried by the trimmer arm, means for latching the trimmer arm to said tangent bar and means for adjusting the pivotal center of the trimmer arm relative to said tangent bar.

8. A trimmer mechanism for abrasive wheels comprising a cylindrical segment, a tangent bar mounted on the periphery of said segment, said bar being free to roll upon the segment but restrained from tangential or radial displacement with respect thereto, a trimmer arm pivoted to said tangent bar, a trimmer carried by the trimmer arm and means for adjusting the pivot center of said trimmer arm relative to the tangent bar in a plane at right angles to the axis of the cylindrical segment.

In testimony whereof, we have hereunto subscribed our names this 16th day of August, 1927.
